[57] CLAIM

The ornamental design for a picture image memory-search apparatus with copying function or the like, substantially as shown and described.

DESCRIPTION

FIG. 1 is a perspective view of a picture image memory-search apparatus with copying function showing my new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof; and FIG. 7 is a bottom plan view thereof.
